GRINDING WHEEL

Carl Wolf, Meriden, Conn.

Application May 16, 1939, Serial No. 273,901

7 Claims. (Cl. 51—209)

This invention relates to grinding wheels, and more particularly to an improved reinforcing means for an annular grinding wheel constructed of plastic abrasive compound, and having an organic binder, such as shellac, silicate, rubber or Bakelite.

Grinding wheels of the above nature are usually made from 6 to 24 inches in diameter, and are often operated at surface speeds higher than 5000 feet per minute so that unless reinforced, said grinding wheels would fly apart, due to the excessive stresses developed at such speeds.

One object of the present invention is to provide an inexpensive reinforcing means for a grinding wheel of the above nature in which the possibility of fractures will be reduced to a minimum.

Another object is to provide a reinforcing means of the above nature which is adapted to be embedded in the wheel during the molding thereof.

A still further object is to provide a reinforced grinding wheel of the above nature which will be simple in construction, relatively inexpensive to manufacture, easy to manipulate, compact, ornamental in appearance, and very efficient and durable in use.

With these and other objects in view, which will appear as the description proceeds, there have been illustrated in the accompanying drawings, several forms in which the invention may be conveniently embodied in practice.

In the drawings:

Fig. 1 is a rear end face view of a cylindrical grinding wheel embodying the features and principles of this invention, and showing one form of reinforcing means.

Fig. 2 is a sectional view taken on the line 2—2 of Fig. 1.

Fig. 3 is a rear end face view of a grinding wheel having a modified form of reinforcing means.

Fig. 4 is a sectional view taken on the line 4—4 of Fig. 3.

Fig. 5 is a fragmentary end view of another modified form of reinforcing means, shown separately from the grinding wheel.

Fig. 6 is a sectional view taken on the line 6—6 of Fig. 5.

Fig. 7 is a side view, partly in section, of an apparatus employed for molding a grinding wheel with the first form of reinforcing means embedded therein.

Fig. 8 is a side view, partly in section, showing the appearance of the first form of grinding

wheel when attached directly to the face of a driving spindle.

Referring now to the drawings wherein like reference numerals designate like parts throughout the several views, the numeral 10 denotes an annular or ring-shaped grinding wheel formed by high-pressure molding from any suitable plastic abrasive compound having an organic binder. A mold suitable for use in molding a grinding wheel of the above nature is shown in Fig. 7, and includes a bottom plate 11, an outer side ring 12 and a central cylindrical core 13. The molding apparatus is adapted to be secured to a face plate 14 of a driving spindle hub 15, by means of a mold cover plate 16 secured to said plate 14 by headed screws 17. The core 13 is of the proper size to correspond with the height of the grinding wheel being molded, and the abrasive material is compressed tightly within the outer ring 12 and between the mold bottom 11 and the cover plate 16. A narrow wheel centering hub 18 is preferably provided on the plate 16 to form a recess 19 in the resulting grinding wheel 10.

Each of the three forms of reinforcing means shown in the drawings is adapted to be secured against the face of the cover plate 16 within the mold, by screws 20, which are relatively longer than the screws 17 which pass through the face plate 14 and which are adapted to be driven into a plurality of sleeve-like nuts 21, three in this instance. The nuts 21 are preferably roughened on their outer periphery, such as by knurling. In the form shown in Figs. 1 and 2, the nuts 21 are secured, as by spot-welding, to the points 23 on the inside of a flat circular wire or metal strip 22, although said nuts may be secured to the outside of said strip if desired. The flat metal wire 22 is preferably roughened, corrugated or serrated on its inner and outer flat surfaces and edges to insure that the abrasive material will more efficiently adhere thereto.

After being molded, the grinding wheel 10 will be removed from the mold and may, if desired, be used with the face plate 14 secured to the cover plate 16, as shown in Fig. 7, or the cover plate 16 may be removed from the assembly and the wheel 10 secured to a face plate 24, see Fig. 8, provided with a centering hub 25, by means of screws 26a threaded into the knurled nuts 21.

When grinding wheels of larger size are to be molded, the reinforcing means will preferably include an additional ring 26 of flat metallic wire or strip material spot welded at 27 to the inside of the knurled nuts 21 (see Figs. 3 and 4).

A further modified form of the invention is shown in Figs. 5 and 6, wherein a looped U-shaped strap 28 is disposed to overlie and embrace each of the nuts 21 with the foot ends of said straps spot-welded at 29 to the flat wire ring 22.

In all instances, the nuts 21 and the rings 22 and 26 are disposed flush with the rear face of the grinding wheel 10 and are embedded in the interior thereof. By means of this construction, 10 a very efficient and durable reinforcing means for the grinding wheel 10 is provided, which may safely be used at very high operating speeds and for heavy grinding work. It will be understood that the word "welding" as employed in this application, includes any method of securing the anchoring lugs to the ring member with or without the use of high temperature and pressure.

While there have been disclosed in this specification several forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a grinding wheel of molded abrasive material and having a flat rear face, reinforcing means including a plurality of nuts spaced apart about the wheel, and a ring of flat strip metal surrounding said nuts and spot-welded thereto, said nuts and ring being disposed with their ends and edge respectively flush with the rear end face of said wheel and embedded in the abrasive material of said wheel.

2. In a grinding wheel of molded abrasive material and having a flat rear face, reinforcing means including a plurality of nuts embedded in said wheel flush with the rear end thereof, and a ring of flat strip metal spot-welded to each of said nuts and also embedded in the abrasive material of said wheel, a face plate abutted

against the rear end of said wheel, and screws passing through said plate and screw threaded into said nuts to secure said wheel to said plate.

3. In a grinding wheel of molded abrasive material and having a flat rear face, reinforcing means including a plurality of nuts spaced apart about said wheel, a ring of flat strip metal spot-welded to the outer side of each of said nuts, and a second ring of flat strip metal spot-welded to the inner side of said nuts, said nuts and rings being embedded as a unit in the abrasive material of said wheel flush with the rear end face thereof.

4. In a grinding disk constructed of molded abrasive material and having a flat rear face, a reinforcing and attaching means comprising a plurality of nuts embedded in the back of said wheel and a metal ring surrounding said nuts and welded thereto also embedded in the back of said wheel.

5. A grinding wheel of the class described comprising in combination, a rotatable support having bolts extending away therefrom in the same direction and in spaced relation, a unitary annulus of abrasive material, a ring member of rigid material embedded in said annulus, and nuts welded to said ring member at spaced points therearound, said nuts being adapted to receive said bolts.

6. In a grinding wheel constructed of molded abrasive material having a flat rear face, reinforcing means including a ring member of rigid material and a plurality of anchoring devices metallurgically secured directly thereto at spaced intervals around the periphery thereof, said ring member and anchoring device being embedded in the material of said wheel during molding.

7. In a grinding wheel constructed of molded abrasive material having a flat rear face, a reinforcing means including a ring member of rigid material and a plurality of anchoring lug members metallurgically secured directly thereto at spaced intervals around the periphery thereof, said ring member and anchoring lug members being embedded in the material of said wheel during molding.

CARL WOLF.
